(57) **CLAIM**

The ornamental design for a power source storage cart, as
shown and described.

DESCRIPTION

FIG. 1 is a side perspective view of a power source storage cart.

FIG. 2 is a front view of the power source storage cart of
FIG. 1.

FIG. 3 is a right side view of the power source storage cart
of FIG. 1.

FIG. 4 is a left side view of the power source storage cart of
FIG. 1.

FIG. 5 is a rear side view of the power source storage cart
of FIG. 1.

FIG. 6 is a top view of the power source storage cart of FIG.
1.

FIG. 7 is a bottom view of the power source storage cart of
FIG. 1.

FIG. 8 is a top view of the power source storage cart of FIG.
1 with a compartment door open; and,

FIG. 9 is another side perspective view of the power source
storage cart of FIG. 1 with a compartment door open.

The broken lines are for the purpose of illustrating the
environment of the design only and form no part of the
claimed design.
